No. 2859

Patented Jan. 14, 1868

United States Patent Office.

JOHN T. WEBSTER, OF NEW YORK, ASSIGNOR TO EDWARD HARVEY,
OF BROOKLYN, NEW YORK.

Design No. 2,859, dated January 14, 1868.

DESIGN FOR A FLOOR OIL-CLOTH PATTERN.

The Schedule referred to in these Letters Patent and making part of the same.

TO ALL WHOM IT MAY CONCERN:

Be it known that I, JOHN T. WEBSTER, of the city, county, and State of New York, have invented a new and original Design for a Pattern to be Printed on Floor Oil-Cloths, in colors similar to those painted on the drawings accompanying this specification, or in other colors substituted in the place of those painted on the drawings accompanying herewith; and I do hereby declare that the drawings that accompany this specification do give and convey to any one skilled in the art of printing floor oil-cloths a more defined and thorough description of the nature of my invention than it is in the power of language otherwise to convey, and it is sufficient to enable any one skilled in the art of printing floor oil-cloths to use my invention.

What I claim as my invention, and desire to secure by Letters Patent, is—

The configuration of the design hereunto annexed, when made by being printed upon floor oil-cloth or other fabric, in the form similar to the drawings accompanying this specification.
